UNITED STATES PATENT OFFICE.

GEORGE C. ANDREWS, OF MINNEAPOLIS, MINNESOTA.

DESIGN FOR A TRACTION-ENGINE BODY.

46,871.

Specification for Design.

Patented Jan. 26, 1915.

Application filed April 29, 1914. Serial No. 835,317. Term of patent 14 years.

To all whom it may concern:

Be it known that I, GEORGE C. ANDREWS, a citizen of the United States, residing at Minneapolis, in the county of Hennepin and State of Minnesota, have invented a new, original, and ornamental Design for a Traction-Engine Body, of which the following is a specification, reference being had to the accompanying drawings, forming part thereof.

Figure 1 is a side elevation of a traction

engine body embodying and illustrating my novel design. Fig. 2 is a front elevation of said traction engine body.

I claim:

The ornamental design for a traction engine body, as shown.

GEORGE C. ANDREWS.

Witnesses:

A. M. ROYAL,
F. A. WHITELEY.
